INDUSTRIAL SHIPPING CONTAINER

Roy G. Churan, Oak Lawn, Ill., assignor to Bennett
Industries, Inc., Peotone, Ill., a corporation of Delaware

Filed June 20, 1967, Ser. No. 7,528

Term of patent 14 years

Int. Cl. D9—04, 05, 09

U.S. Cl. D9—216

FIGURE 1 is a front elevational view of an industrial shipping container showing my new design, the rear being substantially the same in appearance;

I claim:

The ornamental design for an industrial shipping container, substantially as shown and described.
